CLAIM

The ornamental design for a dispenser holder, as shown and described.

DESCRIPTION

FIG. 1 is a front perspective view of a dispensing holder showing our new design;

FIG. 2 is a front side elevation thereof;

FIG. 3 is a right side elevation thereof;

FIG. 4 is a backside elevation view thereof;

FIG. 5 is a left side elevation thereof;

FIG. 6 is a top plan view thereof; and,

FIG. 7 is a bottom plan view thereof.

The broken lines shown in the figures represent portions of the dispenser holder that form no part of the claimed design.
